Henry Williams.

UNITED STATES PATENT OFFICE.

GEORGE D. COREY, OF LOWELL, MASSACHUSETTS, ASSIGNOR TO CHARLES M. HOSMER, OF SAME PLACE.

JAR OR BOTTLE FOR FRUIT, MILK, &c.

SPECIFICATION forming part of Letters Patent No. 380,091, dated March 27, 1888.

Application filed May 23, 1887. Serial No. 239,061. (No model.)

To all whom it may concern:

Be it known that I, GEORGE D. COREY, a citizen of the United States, residing at Lowell, in the county of Middlesex and State of Massachusetts, have invented new and useful Improvements in Jars or Bottles for Fruit, Milk, &c., of which the following is a specification.

My invention relates more particularly to jars or bottles of glass or other similar material, and especially to the cover thereof and means for holding said cover in place.

My invention is illustrated in the accompanying drawings, in which similar letters of reference refer to similar parts, and in which— Figure 1 is a view in perspective of a portion of a fruit or milk jar, its cover-clamp, and its cover. Fig. 2 is a central vertical section of the same, and Fig. 3 is a view of the bail or cover-clamp removed from the jar.

A represents the body of the jar, which is provided near its mouth with the annular ledge *a*, constituting the support for the rubber or equivalent sealing-band *b*. A portion, *A'*, of the jar *A*, near the mouth thereof and below the ledge *a*, is made in the shape of the frustum of a cone, with its larger base uppermost, and is made in this shape in order that the clamp which holds the cover in place may engage with this frustum in whatever angular position the cover *B* may be placed upon the band *b*. The cover *B* is provided with the lower sealing-rim, *B'*, which rests upon the sealing-band *b*, and is preferably provided with the upper rim, *B''*, which is elevated above the main body of the cover, and is intended to serve as a surface upon which the jar may securely rest when inverted for storage purposes. This inversion of the jar has been found to be desirable with older forms of jars sealed by rubber bands, since in such cases the contents of the jars have, after long periods, been found to be preserved in better condition than the contents of those filled at the same time with similar substances and which were not inverted for storage.

In order that the jars may stand securely when inverted as described, and in order that the cover-clamp may be properly held in position, the diametrically-opposed grooves *C* are usually made through the rim *B''* and prefera-

bly fully as deep as the diameter of the wire 50 which forms the cover-clamp. The bottom of the grooves *C* are preferably made, as shown in Figs. 1 and 2, to form an extensive surface for contact with the cover-clamp. This extensive surface is desirable, because the material of the 55 cover will in that case be less likely than otherwise to have its surface broken.

The cover-clamp which holds the cover down upon the sealing-band *b* is provided with the horizontal bars *D*, which may be joined 60 as shown in Fig. 1, or in any other convenient and desirable way, or which may terminate at or near the inner edge of the upper rim, *B''*. In case the bars *D* do not form one continuous bar, as shown in Fig. 1, a wire of larger diameter must be necessarily employed from which to make the cover-clamp than would be otherwise necessary.

Joined to the horizontal parts *D* are the elastic arms *D'*, which are shown as being substantially vertical, in order that they may not project beyond the jar unnecessarily, and to these arms *D'* are joined the inwardly-projecting portions *D''* thereof, which press firmly against the frustum *A'* with an elastic pressure when the clamp is in its operative position, as shown in Fig. 2. The inwardly-projecting portions *D''* are usually joined by the curved elastic stop-bar *D'''*. This jar is sealed by placing the cover *B* upon the sealing-ring *b*, 80 that rests upon the ledge *a* of the jar *A*, and then placing the cover-clamp in place in the grooves *C* with the portions *D'* nearly horizontal. The clamp is then rotated in the grooves *C* and until the stop-bar *D'''*, which moves 85 downwardly during this rotation, strikes the body of the jar. When this occurs, the portions *D''* have just passed the perpendicular position on account of the dimensions of the parts of the clamp, and for the same reason 90 they are also pressing with an elastic and firm pressure against the sides of the frustum *A'*. The angle of this frustum is so made that when the cover-clamp is in the locking position shown in Fig. 1, the portions *D''* pressing 95 against the sides of said frustum, the cover *B* will be held to the mouth of the jar with a continuous elastic pressure. To open the jar, it is

only necessary to relieve this elastic pressure by raising the stop-bar D", after which the cover may be readily removed in the usual manner.

What I claim as new, and desire to secure by Letters Patent, is—

1. The jar provided with a conical frustum having its larger base uppermost near its mouth and a sealing-band-supporting ledge between said larger base and said mouth, combined with a sealing-band resting on said ledge, a cover with a downwardly-extending sealing-
rim resting on said sealing-band, and an upwardly-extending rim upon which the structure securely rests when it is stored in an inverted position, said upwardly-extending rim being provided with diametrically opposed deep grooves, the cover-clamp resting in said grooves and provided with the downwardly and inwardly projecting arms, pressing with an elastic pressure on the sides of said frustum, and the elastic curved stop-bar connecting said downwardly-extending arms, substantially as described, and for the purposes specified.
2. The jar provided with a conical frustum having its larger base uppermost near its mouth

and a sealing-band-supporting ledge between said larger base and said mouth, combined with a sealing-band resting on said ledge, a cover with a downwardly-extending sealing-
rim resting on said sealing-band, and an upwardly-extending rim upon which the structure securely rests when it is stored in an inverted position, said upwardly-extending rim being provided with diametrically opposed deep grooves, the cover-clamp resting in said grooves and provided with the downwardly and inwardly projecting arms, pressing with an elastic pressure on the sides of said frustum, and the elastic curved stop-bar connecting said downwardly-extending arms, substantially as described, and for the purposes specified.

GEORGE D. COREY.
